UNITED STATES PATENT OFFICE.

EDWARD C. OBERMEYER, OF NESSEN CITY, MICHIGAN.

ADJUSTABLE LADDER.

1,352,830.

Specification of Letters Patent. Patented Sept. 14, 1920.

Application filed October 4, 1919. Serial No. 328,479.

To all whom it may concern:

Be it known that I, EDWARD C. OBERMEYER, a citizen of the United States, residing at Nessen City, in the county of 5 Benzie and State of Michigan, have invented a new and useful Adjustable Ladder, of which the following is a specification.

My invention relates to new and useful improvements in adjustable ladders, and an 10 important object of the invention is to provide a device of this nature having supplemental legs which may be readily adjusted to support the ladder upon uneven or even surfaces and will insure the ladder of 15 stability.

Another important object of the invention is to provide a device including supplemental legs which are readily adjustable and so arranged as to prevent lateral movement 20 of a ladder to which they are attached when the ladder is being used.

Another object of the invention is to provide a device which is strong, durable, which may be applied to ladders now in use, may 25 be manufactured at a minimum cost, and which is highly efficient in practice.

With the above and other objects in view which will appear as the description proceeds, the invention resides in the combination 30 and arrangement of parts and in the details of construction hereinafter described and claimed, it being understood that, within the scope of what is claimed, changes in the precise embodiment of the invention shown 35 can be made without departing from the spirit of the invention.

In the accompanying drawings, forming a part of the description and wherein like numerals are employed to designate like 40 parts throughout the same.

Figure 1 is a front elevation of the ladder resting upon an even surface, the dotted lines showing the position of the movable parts when the ladder is positioned upon an 45 uneven surface;

Fig. 2 is a side elevation of the invention;

Fig. 3 is a transverse section through one of the supplemental legs taken on line 3—3 of Fig. 1.

50 In the drawings wherein for the purpose of illustration is shown a preferred embodiment of my invention, the numeral 4 designates in general a ladder of the well known construction consisting of two parallel side 55 rails 5 connected by rungs 6, while an ordi-

nary support 7 is secured to the upper end of the side rails. The lower ends of the side rails 4 are joined by a suitable brace 8, which is rigidly secured to the side rails of the ladder. The brace leg 9 is equipped 60 with a pair of spaced bars 10, the upper ends of which are pivotally connected to the relative top of the side rails 4, so that when the ladder is to be used, the brace leg 9 may be swung rearwardly of the ladder to incline 65 downwardly from the top of the ladder to engage the ground at a substantial distance from the lower ends of the side rails 5.

A pair of vertical series of notches are provided upon the side rails 5 adjacent the 70 intermediate portion thereof, by securing to each of the side rails 5, a longitudinally extending ratchet bar 11. A bar 12 is pivotedly connected intermediate its ends to the intermediate portion of the brace 8 through 75 the medium of the bolt 13 or other suitable fastening means, and extends laterally beyond the side rails a substantial distance. A bracket 14 is secured to a side face of each end of the bar 12 by means of fastenings 15, and each bracket is offset as at 80 16 to receive and pivotedly connect a supplemental leg 17 to the bar 12 between the bracket and bar 12 by means of a bolt extending transversely through the bar, supplemental legs 17 and bracket 14. 85

The supplemental legs 17 are disposed laterally of the side rails 5 and have their free ends 19 so constructed as to effectively engage the notches of the ratchet bars 11 90 whereby the legs are inclined downwardly and outwardly of the ladder. As clearly shown in Fig. 1, the lower ends of the legs extend a substantial distance below their pivotal connection with the bar 12 whereby 95 the legs may be engaged upon uneven surfaces.

In order to retain the upper ends of the legs in close engagement with the ratchet bars 11, coiled springs 20 are provided and 100 one end of each is secured to its respective supplemental leg 17 at a point a substantial distance above the pivotal connection of the leg with the bar 12 while the opposite end of each spring is secured to the bolt 13 or 105 may be secured to the bar 12 or any other suitable point adjacent the bolt 13.

When it is desired to adapt the ladder to uneven surfaces, the supplemental legs 19 110 may be moved whereby their upper ends

may engage any of the notches of the ratchet bars 11, consequently causing the bar 12 to swing upon its pivot bolt 13. Therefore, when the right hand leg 17 is moved upwardly to engage one of the relative top notches of the bar 11, the bar 12 will swing to cause the left hand to lower carrying with it the left leg 17. This action will cause the upper end 19 of the left hand leg 10 to slide or move downwardly upon the left hand ratchet bar to engage a relatively lower notch, and due to the action of the springs 20, the upper ends of the legs 17 will be securely retained in engagement with their proper notches in the ratchet bars 11 to rigidly support the ladder. No adjustment is necessary for the brace leg 9, as it is merely swung rearwardly of the ladder and engaged with the ground regardless whether 20 the ladder is supported upon an even or uneven surface.

Having thus fully described the invention, what is claimed is:

1. In a device of the character described, 25 a ladder including side rails, said rails hav-

ing a plurality of notches associated therewith, adjustable supplemental legs pivotally connected with the ladder, and springs for retaining one end of each leg in engagement with said notches.

2. In a device of the character described, a ladder including side rails, a ratchet bar secured to each rail adjacent the intermediate portion thereof, a bar pivotally connected to the lower edge of the ladder and extended beyond the side thereof, a supplemental leg pivoted to each free end of said bar, and coiled springs having connection with the lower ends of the ladder and with each supplemental leg above its pivotal connection to normally urge the upper edge of the supplemental legs into engagement with the ratchet bars.

In testimony that I claim the foregoing as my own, I have hereto affixed my signature in the presence of two witnesses.

EDWARD C. OBERMEYER.
